UNITED STATES PATENT OFFICE.

JAMES A. CRAIG, OF NEW ORLEANS, LOUISIANA, ASSIGNOR, BY MESNE ASSIGNMENTS, OF ONE-HALF TO ALEXANDER T. McCURDIE, OF HATTIESBURG, MISSISSIPPI.

LUMBER DRIER.

Application filed August 10, 1920. Serial No. 402,614.

To all whom it may concern:

Be it known that I, JAMES A. CRAIG, a citizen of the United States, residing in New Orleans, in the parish of Orleans and State 5 of Louisiana, have invented certain new and useful Improvements in Lumber Driers, of which the following is a specification.

This invention relates to rotary air driers for drying lumber or other materials in 10 natural air without the aid of heat or fans.

The main object of the present invention is to provide a machine of this kind in which the lumber may be revolved extremely rapidly so as to utilize centrifugal force and 15 at the same time to compress the air to cause it to pass rapidly through the lumber stack without particularly changing the direction of the air or causing any pocketing thereof.

Another object of the invention is to provide a machine of this kind which may be driven at this very high rate of speed so as to be very effective in operation, without the danger of collapse of the machine. 20

Another object of the invention is to provide a machine of the above described kind which may be easily charged with lumber or other material with a minimum of time and labor, and from which the lumber may 25 be as easily removed after drying.

Other objects of the invention will appear as the description proceeds; and while herein minute details of the invention are disclosed, the invention is not limited to 30 these since many and various changes may be made without departing from the scope of the invention as claimed.

In the accompanying drawing showing by way of example one of many possible embodiments of the invention—

Fig. 1 is a side elevation of the drier;

Fig. 2 is a sectional view taken on the line 2—2 of Fig. 1;

Fig. 2^a is a fragmental side elevation showing means for locking the lumber carrying arms in place;

Fig. 3 is an end elevation of the drier;

Fig. 4 is a side elevation of a gudgeon at the end of the supporting axle of the rotor 50 of the drier;

Fig. 5 is a side elevation of a detail showing a partition wall of the compressor for

compressing the air in front of the lumber;

Fig. 6 is a plan view of one of a slidable lumber-spacing device.

55

My improved drier comprises a pair of foundations 10 (Fig. 1) each supporting a standard 11 carrying a bearing 12 between which is disposed a squared wooden horizontal axle 15 provided at each end with a gudgeon comprising a horizontal stub shaft 16 (Fig. 4) rotatably mounted in each of said bearings and provided at its inner end with a squared box 17 receiving the end of and supporting the axle 15. A protecting 60 plate 18 is secured on opposite faces of said axle and said box.

65

Pairs of L-shaped T-arms 20 are secured at intervals on said axle with their angle ends 21 (Fig. 2) engaging said plates and 70 the inner ends of the main part of the arms placed against the side of the axle 15 so that the arms project in approximately radially opposite parallel directions. U-bolts 23 and 24 pass through said plates and axle and 75 engage said angle-ends and arms and clamp said arms in place.

75

Strain rods 25 (Fig. 3) pivotally linked, as at 26, to each of said arms at the angle thereof are normally adapted to be disposed 80 parallel to and in the direction of the adjacent arm of the same pair and have threaded outer ends. A stud bolt 28 (Fig. 5) is mounted on the outer end of each of said arms even with said threaded outer end. 85 Spacing pieces 30 (Fig. 6) provided with inwardly pointed forked ends 31 are adapted to slidably engage the flanges 32 of said T-arms 20 and are adapted to be placed between the individual pieces 34 (Fig. 3) 90 of lumber or other material horizontally disposed on the angle-ends 21 of said T-arms and with their edges disposed against the retreating faces of the flanges 32 of the T-arms.

95

Clamping yokes 35 received on the outer end of said bolts 28 and rods 25 are held in place by nuts 36 on said outer ends for causing said yokes to clamp said lumber against said angle ends 21, thereby to hold the lumber in place.

100

Angle plates 39 (Fig. 1) secured on the ends of said protecting plates 18 carry the lower ends of forwardly disposed side walls

40 secured to the angle plates; and forwardly disposed intermediate partitions 41 (Fig. 5) are secured to the forward web 42 of said T-arms. Horizontally and forwardly disposed inner walls 44 are secured to the inner ends of said side and partition walls; while horizontally and forwardly disposed outer walls 45 connect and are secured to the outer ends of said side and partition walls there-
 5 by to form with said side, partition and end walls a plurality of forwardly disposed box-shaped compressors constituting a visor or hood arranged forward of or at the side of said pile of pieces 34, in the direction of rotation of said pieces, the purpose of which is to compress the air and cause it to pass adversely between the pieces 34.

A drive pulley 47 (Fig. 1) on one stub shaft is driven by a motor 48. A braking pulley 50 on the other stub shaft is engaged by an intermediate shoe 51 carried on a hand lever 52 having its inner end fulcrumed to the adjacent standard 11.

The operation of the drier is very simple. The nuts 36 are removed to permit the strain rods to be dropped down away from parallelism with the associated arm. The arm is then placed in some convenient angle either horizontal or vertical or at an intermediate position and the pieces of lumber placed in one by one, one of the spacing pieces 30 being slipped down against the piece of lumber each time, to hold the pieces of lumber in spaced relation as shown in Fig. 3. When one side of the device is completely filled so as to have the lumber extending from the angle end 21 of each arm to the outer end of the arm, the clamping yoke 35 is put on and the nuts screwed up so as to clamp the lumber tightly against said angle-end. Then the other side of the drier is turned and filled in like manner.

Current is then turned on the motor and the whole of the rotary part of the drier is revolved forwardly in the direction of the arrow of Fig. 3, at a very high rate of speed, so that the centrifugal force acting upon the moisture contained in the lumber and the air compressed in the compressor and passing rapidly against and between the pieces of lumber very quickly dries out the lumber.

The partitions 41 cut off separate portions of the compressors from each other so that they may function independently. Under any circumstances, the ends of the lumber tend to dry first; and if because of uneven lengths, the end compressors do not compress the air as highly as the intermediate compressors, the functioning of the intermediate compressors will be in no way interfered with.

I have found by careful tests that on filling the drier with wet green lumber from the pond and saw and running one mile a

minute for a predetermined period, say sixty minutes, all the free water in the pores, nearly one pound per foot, came out. Then on taking the lumber out and piling it up in the open, the cell walls were still saturated with about the same amount which was in the pores, but hard to get out. By the drier it takes a predetermined period, say four more hours to get the saturated cell-wall moisture entirely out, but by piling it, it comes out of itself at the rate of four to six ounces per foot each day, so that, in one week the lumber is bone dry and ready to ship for dry lumber and is several hundred pounds lighter per thousand feet than kiln or air dried lumber.

Most firms now use the system of heat and fans. This takes six days and six nights to get out one pound per foot; and to get it entirely bone dry as in my process requires from twelve to sixteen days. Air drying in the open takes six months, and heat or hot air is very expensive. There is six per cent insurance difference between the other methods and mine, which is favorable to mine.

Having thus described my invention, I claim:

1. In a drier, a rotatable shaft; a carrier rotatable with said shaft and adapted for retaining therein for rotating therewith piles of spaced pieces of lumber; and air compressors open forwardly and rearwardly and supported forwardly of the forward planes of said piles in close proximity to the faces of the piles and rotatable with said carrier for forcing air directly through the spaces of the piles.

2. In a drier, a rotatable shaft; a carrier rotatable with said shaft and adapted for retaining therein for rotation therewith piles of spaced pieces of lumber; and air compressors open forwardly and rearwardly and supported forwardly of the forward planes of said piles in close proximity to the faces of the piles and rotatable with said carrier for forcing air directly through the spaces of the piles, the compressors being divided into separate air compressing compartments.

3. In a drier, a rotatable shaft; a carrier rotatable with said shaft and adapted for retaining therein for rotation therewith piles of spaced pieces of lumber; and box-form air compressors open forwardly and rearwardly and supported forwardly of the forward planes of said piles in close proximity to the faces of the piles and rotatable with said carrier for forcing air directly through the spaces of the piles.

4. In a drier, a rotatable shaft; a carrier rotatable with said shaft and adapted for retaining therein for rotation therewith piles of spaced pieces of lumber; and box-form air compressors open forwardly and rear-

- wardly and supported forwardly of the forward planes of said piles in close proximity to the faces of the piles and rotatable with said carrier for forcing air directly through the spaces of the piles, the compressors being divided into separate air compressing compartments. 5
5. In a drier, a rotatable shaft; a carrier rotatable with said shaft and adapted for retaining therein for rotation therewith piles of spaced pieces of lumber, the spaces between the pieces being parallel to said shaft; and box-form air compressors open forwardly and rearwardly and supported 10 forwardly of the forward planes of said piles in close proximity to the faces of the piles and rotatable with said carrier for forcing air directly through the spaces of the piles, the compressors having longitudinal partitions for dividing them into separate air compressing compartments. 15
6. In a drier, a rotatable shaft; a carrier rotatable with said shaft and adapted for retaining therein for rotation therewith piles 20 of spaced pieces of lumber, operably controlled means for rotating said shaft; and means for stopping the continued rotation of said shaft and carrier after said means for rotating is stopped. 25
7. In a drier, a rotatable shaft; a carrier rotatable with said shaft and adapted for retaining therein for rotation therewith piles of spaced pieces of lumber; box-form air compressors open forwardly and rearwardly 30 and supported forwardly of the forward planes of said piles in close proximity to the faces of the piles and rotatable with said carrier for forcing air directly through the spaces of the piles; operably controlled 35 means for rotating said shaft; and brake means for stopping the continued rotation of said shaft after said means for rotating is stopped. 40
8. In combination, a horizontal rotary 45 axle; approximately radial arms secured to said axle; and means for securing a pile of spaced pieces of lumber against side walls secured to said axle just forward of the plane of said pieces; and a forwardly and rearwardly open forwardly disposed box-shaped compressor box secured forward of said pile. 50
9. In combination, a horizontal rotary 55 axle; opposite approximately radial arms secured to said axle; means for securing a pile of spaced pieces of lumber against the rear face of said arms; side walls secured to said axle just forward of the plane of said pieces; and forwardly disposed outer 60 and inner walls secured to and connecting the outer ends and the inner ends respectively of said side walls and forming a forwardly and rearwardly open forwardly disposed box-shaped compressor box forward of said pile. 65
10. In a drier, means for revolving a radially disposed pile of pieces of material; and a forwardly disposed forwardly open compressor secured forward of said pile and comprising separated compartments. 70
11. In a drier, means for rapidly moving a pile of pieces of material; and a forwardly disposed compressor secured forward of said pile and comprising compartments side by side. 75
12. In a drier, means for revolving a radially disposed pile of pieces of material; forwardly disposed partition walls secured forward of said pile; forwardly disposed side walls secured at the ends of said pile; and forwardly disposed outer and inner walls and connecting together the outer ends and the inner ends respectively of said side and partition walls and forming a forwardly and rearwardly open forwardly disposed box-shaped compressor box forward of said pile. 80
13. In combination, a horizontal rotary axle; opposite approximately radial arms secured to said axle; means for securing a pile of spaced pieces of lumber against said arms; forwardly disposed partition walls secured forward of said arms; forwardly disposed side walls secured at the ends of said axle; and a forwardly and rearwardly open forwardly disposed box-shaped compressor formed into compartments secured forward of said pile. 85
14. In combination, a horizontal rotary axle; opposite approximately radial T-arms secured to said axle and having forward webs; means for securing a pile of spaced pieces of lumber against the rear face of said arms; angle plates secured on the ends of said axle; forwardly disposed side walls secured to the angle plates; forwardly disposed intermediate partition walls secured to the forward web of said arms; horizontally and forwardly disposed inner walls secured to the inner ends of said side and partition walls; and horizontally and forwardly disposed outer walls connecting and secured to the outer ends of said side and partition walls thereby to form with said side, partition and end walls a forwardly disposed box-shaped compressor. 90
15. In combination, a rotary axle; arms secured to said axle; and means for securing a pile of spaced pieces of lumber against said arms. 105
16. In combination, a horizontal rotary axle; approximately radial arms secured to said axle; and means for securing a pile of lumber against said arms. 110
17. In combination, a rotary axle; approximately radial arms secured on said axle and provided with shoulder forming portions; strain rods pivotally connected to each of said portions and adapted to be disposed parallel to the adjacent arm; and 115
- 120
- 125

- 4 a clamping means on the outer end of said arms and rods.
18. In combination, a horizontal rotary axle; pairs of oppositely projecting arms secured at intervals on said axle and having angle ends engaging said axle; strain rods pivotally linked to said angle ends and adapted to be normally disposed parallel to and in the direction of all arm having 5 threaded outer ends; a stud bolt mounted on the outer end of each of said arms even with said threaded outer end; and clamping means received on the outer end of said bolts and rods.
19. In combination, a horizontal rotary axle; pairs of L-shaped T-arms secured at intervals on said axle with the web forward and their inner end portions and angle ends engaging said axle and their arms parallel 10 and projecting in approximately radially opposite directions; U-bolts passing through said axle and engaging said angle-ends and the arms and clamping said arms in place; strain rods pivotally linked to each of said 15 arms at the angle thereof and normally adapted to be disposed parallel to and in the direction of the opposite arms of the same pair having threaded outer ends; a stud bolt mounted on the outer end of each 20 of said arms even with said threaded outer end; a clamping yoke received on the outer end of said bolts and rods; and nuts on said outer ends for holding said yoke in place and causing the latter to clamp a pile of 25 pieces of material against said angle ends and thereby to hold the pieces in place between the arm and strain rod.
20. In combination; a horizontal rotary axle; opposite approximately radial T-arms secured to said axle and having flanges at their rear part; means for securing a pile of spaced pieces of lumber against the rear face 30 of said arms; spacing pieces provided with inwardly pointed forked ends adapted to 35 slidably engage the flanges of said T-arms and adapted to be placed between the individual pieces of said lumber horizontally disposed with their edges disposed against the rear faces of said T-arms; and a forwardly and rearwardly open forwardly dis-
- posed box-shaped compressor box secured to said arms forward of said pile.
21. In combination, a pair of foundations; a standard on each foundation; a bearing on each standard; a squared horizontal axle between said standards; a gudgeon comprising a horizontal stub shaft rotatably mounted in each of said bearings and provided at its inner end with a squared box receiving the end of said axle and supporting the axle; opposite approximately radial arms secured to said axle; means for securing a pile of spaced pieces against the rear face of said arms; a forwardly and rearwardly open forwardly disposed box-shaped compressor secured to said arms forward of said pile; a drive pulley on one of said shafts and a braking pulley on the other; a motor for driving said drive pulley; and a brake-hand lever having an intermediate pulley-engaging shoe, and its inner end fulcrumed to the adjacent standard.
22. In a lumber drier, the combination with a horizontally rotatable axle, of radial arms secured in said axle, spacing means on said arms for retaining lumber, and a plurality of projections attached to and forward of said arms whereby to allow the air to pass between said projections and through said lumber on the arms upon rotation of said axle.
23. In a rotary drier, the combination with a horizontally rotatable axle, of a plurality of radial arms secured to said axle, spacing members attachable to said arms, 75 said members serving to support lengths of lumber thereon and a plurality of flat members projecting perpendicularly along the length of the arms and forward of said arms, for causing compression and passage 80 of air between said projections, as the axle is rotated.
24. In a rotary drier, the combination with a plurality of radial arms movable about a common center, an open compressor 90 box attached to and forward of said arms, and means for rotating said arms whereby to cause compression and passage of air through the lumber supported on said arms.

JAMES A. CRAIG.
